UNITED STATES PATENT OFFICE.

JOHN FAIX AND SAMUEL FAIX, OF SAN FRANCISCO, CALIFORNIA.

COMBINATION-TOOL.

1,268,558.

Specification of Letters Patent. Patented June 4, 1918.

Application filed December 11, 1916. Serial No. 136,346.

To all whom it may concern:

Be it known that we, JOHN FAIX and SAMUEL FAIX, citizens of the United States, residing at San Francisco, in the county of 5 San Francisco and State of California, have invented new and useful Improvements in Combination-Tools, of which the following is a specification.

It is a common occurrence with wood-10 workers, and persons in general working in proximity to wood having rough surfaces, to have a splinter of wood enter the hand. Sometimes, especially if the splinter is a very small one, it is difficult to extract the 15 splinter from the hand by an ordinary tool, such as a pocket knife. The object of the present invention is to provide a small implement, convenient for carrying in the pocket, by which such splinters, and other 20 small objects, can be easily and quickly extracted from beneath the skin and other injuries of a similar character wholly or partly repaired.

In the accompanying drawing, Figure 1 25 is a side view of our improved implement closed; Fig. 2 is a plan view of the same; Fig. 3 is a side view of the implement, showing two parts thereof partly extended; Fig. 4 is a broken side view, showing a blade 30 fully extended; Fig. 5 is a similar view showing a pair of tweezers fully extended; Fig. 6 is a cross sectional view on the line 6-6 of Fig. 2.

Referring to the drawing, 1 indicates a 35 case or frame for the implement, which is here shown as formed of a single piece of sheet metal bent into a trough-shaped form, the sides of the case being at one end pressed into contact with each other, as shown at 2, 40 and having an apertures 3 therethrough, and at the other end being pressed closer to one another than at the middle, as shown at 5, the back being cut away at said latter end.

Between said sides at said latter end is 45 pivoted, upon a pivot pin 8 extending through said sides, a pair of tweezers 9, said tweezers being made of a single piece of metal folded double in the middle, the two halves of the tweezers diverging from said 50 pivot to points near their free ends 10 and then converging, each of said free ends being sharply pointed. The sharply pointed ends 10 of the tweezers permit the tweezers to be inserted below the skin to grasp a minute object, as a small splinter, embedded in the

hand beneath the skin. For withdrawing the tweezers from the frame or case, each side of the tweeler is formed in its outer surface, near its outer edge, with a longitudinally extending groove 11 to receive a 60 finger nail, and the sides of the case 1 are cut away, as shown at 12, to permit of easy access of the finger nails to the grooves. The sides of the tweezers, when free, are so far apart that they have to be sprung inward toward each other to be received within the walls of the case, and, when received therebetween, they spring outward and press against said walls and are held by such pressure in the case with the points of the 70 tweezers touching each other. However, after removal from the case, said tweezers spring outward still farther from each other, so that their points are spaced a convenient distance apart. 75

Between the two halves of the tweezers there is pivoted upon the pivot pin 8 a blade 13, said blade having a knife edge 14, terminating in a sharp broad prong 15, said blade having also at the back a slender pricker 16 80 tapering to a sharp point, and curved upwardly, or out of the plane of the blade, at its point, as shown at 17 in Fig. 2. Said pricker forms an effective implement for penetrating the skin and removing small objects which have been lodged beneath its surface. The prong 15 which is of much greater width and therefore stronger than the pricker 16, is used for dislodging objects offering considerable resistance. The knife 85 edge may be used for trimming the nails. Said blade is also roughened, as shown at 18, on one or both sides, here shown as on one side, for the purpose of filing the nails. The blade near its pivot 8 is cut away to 90 form a shoulder 19 which rests upon a shoulder 20 formed by the doubled central portion of the tweezers, while the blade itself swings on said pivot 8 through the cutaway front part of the central portion of the 100 tweezers. In the closed position of the tweezers its two halves are pressed toward each other so that they are pressed against the sides of the blade near the pivot so as to exert sufficient friction against said sides 105 to prevent it from slipping from any position to which it has been moved.

The blade can be withdrawn from between the tweezers by first pushing gently outward upon a part of its front edge which 110

lies between recesses 20 in the inner edges of the two halves of the tweezers, and then grasping between the thumb and finger.

We claim:—

5 In combination, a case formed of a single piece of sheet metal having a trough-shaped form, the sides of the case at one end extending in contact with each other and at the other end extending nearer together than
10 in the main body of the case and having a

pivot pin therethrough, a pair of tweezers formed of a single piece of spring sheet metal doubled in the middle and pivoted on said pivot pin between the sides of the case, and a pricker pivoted on said pivot pin between the two halves of the tweezers and frictionally engaging said halves when said halves are within the case.

JOHN FAIX.
SAMUEL FAIX.
